UNITED STATES PATENT OFFICE.

JACOB PFEFFER, OF WATERLOO, IOWA.

PIE CABINET.

Application filed April 21, 1921. Serial No. 463,413.

To all whom it may concern:

Be it known that I, JACOB PFEFFER, a citizen of the United States, residing at Waterloo, in the county of Blackhawk and State 5 of Iowa, have invented certain new and useful Improvements in Pie Cabinets, of which the following is a specification.

The object of this invention is to provide a strong, durable and inexpensive cabinet 10 by the use of which pies or similar articles of food may be transported without injury and maintained in a thoroughly sanitary condition. The invention seeks to provide a cabinet, the parts of which may be easily 15 separated when cleaning or repairs may be necessary, and a further object of the invention is to provide a cabinet of such a construction that a number of the cabinets may be piled one upon another for transportation 20 or storage and will be effectually held against accidental displacement. Other objects will appear incidentally in the course of the following description and the invention resides in certain novel features which 25 will be particularly pointed out in the claims following the description.

In the accompanying drawings—

Figure 1 is a perspective view of one embodiment of my invention; 30 Fig. 2 is a horizontal section of the same; Fig. 3 is a vertical longitudinal section thereof.

In carrying out the invention, I employ a base which is in the form of an elliptical 35 rim 1 having straight sides and semi-circular ends and provided on the inner faces of is straight side portions with angle iron brackets 2 which serve as reinforcements to prevent buckling of the side portions of the 40 rim and also add to the supporting surface. I also secure to the straight side portions of the base, side walls or plates 3 which, like the rim, may conveniently be formed of sheet metal so as to avoid undue weight and 45 expense. These side plates may be soldered or otherwise firmly united with the base and each side plate at its upper end is bent inwardly to provide an overhanging flange 4. The rim 1 is provided with a ledge or shoulder, 50 and upon the said ledge or shoulder, I secure circular bottom plates 6 which may meet at the center of the device and are provided each with an annular flange or rib 7. Inner semi-cylindrical walls 8 are fitted 55 against the inner portions of the flanges 7 and have their straight longitudinal edges

engaged in vertical reentrant flanges 9 formed along the ends of the side walls or plates 3, as shown most clearly in Fig. 2. I further provide rails or rims 10 at the edges 60 of the circular bottom plates 6 and these rails or rims serve as guides and retainers for the lower ends of semi-cylindrical doors 11. The doors are mounted for sliding movement, and it will be readily understood 65 upon reference to Figs. 2 and 3 that when in closed position each door will co-operate with one of the semi-cylindrical walls 8 to define a cylindrical compartment in which are shelves 12 upon which the pies or other 70 commodities are placed. When the door is in open position, it will fit within the concavity of the adjacent semi-cylindrical wall, as clearly shown in Fig. 2. Each door is provided at its free edge with an outwardly 75 projecting flange 13 which is adapted to be engaged by a spring latch 14 upon the front side wall or plate 3 so that the door will be yieldably held in closed position. The spring latch 14 is preferably formed or constructed to provide an eye or loop 15 at its 80 free end and upon the outer side of the door, adjacent the free edge thereof, is a loop 16 which, in the closed position of the door, will lie close to the eye 15, as shown in Figs. 1 85 and 2. When the cabinet is to be shipped, a sealing wire and tag may be engaged through the adjacent eyes 15 and loops 16 in an obvious manner.

The upper ends of the compartments are 90 closed by circular covers 17 having depending rims 18 at the outer portions of their edges and having smaller flanges 19 at the inner portions of the edges to which the upper ends of the inner walls 8 may be soldered 95 or otherwise securely fastened. The lips 13 formed at the outer edges of the doors are cut away or reduced at their ends, as shown most clearly at 20 in Fig. 3, so that the lip or flange may project outwardly between 100 the members 10 and 18 and thereby aid in guiding the door in its movements. The several shelves 12 are preferably constructed of sheet metal and are provided with reinforcing rims or annular flanges 21 at their 105 edges on their under sides so as to guard against buckling and also avoid the liability of the user cutting his hand while placing the commodities within the cabinet or removing them therefrom. Long securing 110 bolts 22 are inserted through the bottom plate 6 and the several shelves as well as

through the covers 17 and around these bolts between the several shelves are spacer sleeves 23 whereby the shelves will be supported in proper spaced relation. Nuts 24 are mounted upon the lower ends of the bolts and are adapted to be turned home against the bottom plate 6 so as to secure the parts firmly together.

Extending longitudinally of the cabinet 10 upon the tops 17 is a brace plate 25 having upstanding lugs 26 at its ends and the innermost bolts 22 are inserted through this brace, as will be readily understood upon reference to Figs. 1 and 3. A handle or bail 15 27 is disposed transversely of the device at the center of the same and has its ends engaged under and secured to the flanges 4 by soldering or in any other convenient or preferred manner.

20 It will be readily noted that the vertical edges of the front and rear side walls 3 are disposed upon the transverse diameter of the shelves and, consequently, one-half of each shelf projects beyond the edges 25 of the said walls. When the door is in closed position, the shelves and their contents will be entirely enclosed or housed in the compartment defined by the door and inner wall 8, a rim 6 and a cover 17, but, 30 when the door is opened, one-half of each shelf in said compartment will be exposed and the door will be housed between the inner edges of the shelves and the adjacent wall 8. The commodities may be thus readily placed upon or removed from the shelves and thorough inspection may be given the articles before removal so that the user may be sure that the desired article is being removed. If it be desired to transport or 40 store a large number of the cabinets, they may be placed one upon another and the lugs 26 and handle 27 of a lower cabinet will fit within the brackets 2 and circular end portions of the rims 1 of a superposed cabinet and thereby serve to prevent accidental dislodgment of the latter. If it be desired to clean or repair the cabinet, the nuts 24 may be readily removed from their respective bolts and after the bolts have 45 been withdrawn the spacing sleeves 23 will, of course, be released from the shelves and

the shelves and the sleeves may be easily withdrawn from the cabinet. It will also be readily understood that after the bolts have been withdrawn the covers 17 may 55 be removed and the doors also withdrawn so that all parts of the cabinet will be accessible and may be very easily cleaned. The device is very simple in its construction and may be produced at a low cost while it will 60 be found highly efficient for the purposes for which it is designed.

Having thus described the invention, what is claimed as new is:

1. A cabinet comprising an elliptical rim 65 having semi-circular ends and straight side portions and constituting a base, circular bottom plates secured upon said base, semi-cylindrical walls erected upon the inner portions of the said bottom plates, circular 70 covers secured to the upper ends of the semi-cylindrical walls, means extending through the covers and the bottom plates to secure the parts together, circular shelves carried by said securing means, and semi-cylindrical doors slidably mounted between 75 the covers and the bottom plates and adapted in open position to be housed within the semi-cylindrical walls.

2. A cabinet comprising an elliptical rim 80 having semi-circular ends and straight side portions and constituting a base, circular bottom plates secured upon the ends of said base, straight walls secured to and rising from the straight side portions of the base, 85 semi-cylindrical walls secured to and rising from the inner edge portions of the circular bottom plates, said semi-cylindrical walls being disposed between the straight side walls and having their vertical end 90 edges secured to the vertical end edges of said straight walls, circular covers secured to the upper ends of the semi-cylindrical walls, semi-cylindrical doors slidably mounted between the covers and the bottom plates and adapted in open position to be housed within the semi-cylindrical walls, 95 and interengaging means on the doors and one of the straight walls to hold the doors in open position.

In testimony whereof I affix my signature:

JACOB PFEFFER. [L.S.]
